RACK FOR A HAND TRUCK

Morris F. Ruffley, Jr., Silverton, Ohio, assignor to The Coca-Cola Bottling Works Company, Cincinnati, Ohio, a corporation of Ohio

Filed May 11, 1967, Ser. No. 7,073

Term of patent 7 years

(Cl. D14—3)

FIG. 1 is a front elevational view of a rack for a hand truck, showing my new design;

FIG. 2 is a top plan view thereof;

FIG. 3 is a rear elevational view thereof;

FIG. 4 is a bottom plan view thereof;

FIG. 5 is a side elevational view thereof; and

FIG. 6 is another side elevational view thereof.

I claim:

The ornamental design for a rack for a hand truck, as shown.
